PUMP

Dwight L. Hopper, Pittsburgh, Pa., assignor, by
mesne assignments, to the United States of
America as represented by the United States
Atomic Energy Commission

Application May 24, 1946, Serial No. 671,974

3 Claims. (Cl. 219—38)

1

My invention relates to a diffusion pump, and particularly to a heating element for an oil diffusion pump having high heat requirements.

In the operation of vacuum pumps of the oil diffusion type, it is customary to provide a volatile oil and apply heat thereto to produce the entraining or pumping vapors. With the increase in pumping speeds as well as the differential pressures against which the pumps are operated, it is necessary to supply ever increasing quantities of heat to the vaporizing material.

Difficulty has been experienced either in passing necessary heat into the boiler or in excessive deleterious distillation of the vapor producing material. In order to eliminate this difficulty, I have provided an internal heater composed of a bare heating element or wire of relatively great length and large cross sectional area immersed directly in the vapor producing material and supported in insulated relation from the container walls, it being desirable to support the heating element in such manner that very small portions of the heating element are in contact with the insulating support in order to prevent spot temperatures of excessive value which would produce destructive distillation of the vapor producing material.

It is, accordingly, an object of my invention to provide a heating element directly in contact with the vapor producing materials.

It is a further object of my invention to provide a heating element having a low watt density per unit area of the heating element.

It is a further object of my invention to provide a heating element suspended in substantially oil immersed position in the boiler.

Other objects and advantages of my invention will be apparent from the following detailed description taken in conjunction with the accompanying drawing, in which:

Figure 1 is a plan view of a heating element according to my invention;

Fig. 2 is a sectional elevation of a portion of a pump embodying my invention; and

Fig. 3 is a fragmentary illustration of a modification according to my invention.

In the preferred embodiment of my invention, the heating element 1 is composed of a relatively stable resistance material, preferably such as the alloys now sold under the name Nichrome and comprising a wire or preferably a ribbon of relatively large surface area per unit of length to produce a relatively low wattage output per unit of the surface area of the heating element.

This heating element 1 is wound into a con-

2

tinuous spiral with the ends 2 and 3 supported on lead-in structures 4 and 5 extending through the wall 6 of the boiler container. Preferably these lead-in structures 4 and 5 are of the insulated bushing type shown in Patent No. 2,300,941. In order to provide insulation between the wire 1 and the side 6 of the boiler ceramic supports 10 are provided secured permanently to the bottom of the boiler. Supporting grooves 11 are provided in the upper surface of the ceramic insulators 10, the shape of the grooves 11 being such that the heating element 1 makes a three point contact with the insulating material 10. That is, at the entering and exit edges 15 from the groove 11, the contact element will make a point contact with the inside edge 12 of the groove 11 while at substantially the central portion of the groove 11, the heating element 1 will make a point contact with the outside edge 13 of the groove 11. In this manner, oil 15 may flow freely around substantially the entire surface of the heating element 1 and thus prevent excessive hot spots which might burn out the heating element 1 or cause destructive distillation of the vapor producing fluid 15.

Instead of using fixed bar type insulating supports 10, it is possible to provide a plurality of bead-like elements 20 to support the heating element 1. In the event such bead-like elements 20 are used, it is necessary to provide these elements with relatively large interior openings 21 so that the heating element 1 makes very limited contact with the inner surface of the insulating beads 20 and allows the insulating oil 15 to flow freely around all portions of the heating element 1.

While for purposes of illustration I have shown and described preferred embodiments of my invention, it will be apparent that changes and modifications can be made therein without departing from the true spirit of my invention or the scope of the appended claims.

I claim as my invention:

1. In a boiler for a vacuum pump a heating element immersed in the vaporizing material, said heating element being in direct contact with said vaporizing material, insulated lead-in terminals for said heating element, insulating means for supporting said heating element out of contact with the walls of said boiler, said supporting elements making a three point contact with said heating electrode.

2. A heating element for a vapor evolving boiler comprising a metallic container, a quantity of vapor evolving material in said container,

a metallic heating element in direct contact with said vaporizing material, insulated lead-in terminals for said heating element and insulating supports for said heating element, said insulating supports making spaced apart point contacts with said heating element whereby the vaporizing material comes into contact with the maximum portion of the surface of said heating element.

3. A heating element for a vapor evolving boiler comprising a container of conducting material, a quantity of vapor evolving oil in said container, a heating resistor having low wattage per unit of surface area in direct contact with said oil, insulated lead-in terminals for said re-

sistor, ceramic insulator supports for said resistor, said supports having grooves making three point contact with said resistor.
